UNITED STATES PATENT OFFICE.

CHARLES GOODYEAR, OF NEW YORK, N. Y., ASSIGNOR TO J. B. COLT COMPANY, A CORPORATION OF NEW YORK.

ACETYLENE-GAS GENERATOR.

SPECIFICATION forming part of Letters Patent No. 738,431, dated September 8, 1903.

Application filed June 24, 1901. Serial No. 65,856. (No model.)

To all whom it may concern:

Be it known that I, CHARLES GOODYEAR, a citizen of the United States, and a resident of the city and State of New York, have invented certain new and useful Improvements 5 in Acetylene-Generators, of which the following is a specification, accompanied by a drawing.

The object of the invention is to improve 10 and render more even and reliable the operation of generators for acetylene and other gases of the type in which the gas is generated by feeding a solid gas-making substance into water or other liquid. Irregularity in 15 the action of such a generator when the carbid holder or hopper is carried upon the rising and falling gas-holder bell may arise from the diminishing weight of carbid or solid substance carried by the bell and may also arise, 20 particularly in the case of acetylene-generators, from the formation of floating masses of lime, which obstruct the dropping of the carbid into the water. These defects the 25 present invention overcomes by providing means for compensating any decreasing weight of carbid and means for agitating the surface of the water where the carbid drops into it in a way to prevent the formation of floating obstructions.

30 In the accompanying drawing the figure is a central vertical section of one form of acetylene-generator embodying the present improvements.

The rising and falling members and, indeed, 35 all the parts are shown somewhat diagrammatically, because the invention does not concern details of design.

The carbid-hopper 20 is mounted upon a neck 21 on the rising and falling gasometer-bell 22. The water-holding vessel 23, provided with a water seal 24 for the bell, which may or may not be separate from the generating-space, is preferably provided with a raised plate or table 26, standing on legs 27 45 in position to be engaged by the rod 28 of the carbid-feeding valve 29. According to this construction it will be seen that the means for feeding carbid are controlled by the gas.

The details of the carbid-feeding mechanism 50 are not essential to the invention. The rise and fall of the bell 22 causes the rod

28 to open and close the carbid-feeding valve 29. As the weight of carbid diminishes the pressure on the gas is proportionately reduced, and to compensate for this I provide a means 55 for maintaining the pressure constant. This means in the form illustrated consists of an air-tight water-holding vessel 30, connected by a chain 31 and pulleys to act as a counter-weight to the bell. Depending from the 60 water-holding vessel 30 is a flexible connection 32, having a downwardly-directed mouth 33, which dips into the water that seals the bell. The mouth 33 may dip into a lateral extension of the vessel 24, which communicates freely with the water within through an opening 133. So long as no bubbles of air can rise through the connection 32 the water contained in the vessel is prevented by atmospheric pressure from discharging through the 70 connection 33. As soon, however, as the diminishing weight of carbid on the bell reduces the gas-pressure slightly and allows the depth of water surrounding the bell to diminish correspondingly the mouth 33 of 75 the connection 32 is exposed and air-bubbles pass up through connection 32, displacing an equal amount of water and lightening the vessel 30. The lightening of the vessel 30 increases the pressure by increasing the 80 weight that rests upon the gas in the generator, and this compensating action continues until normal pressure is established and the mouth 33 of the connection 32 is again water-sealed. 85

The agitating device for the water in the generator may preferably consist of a pivoted grid or sieve 40, mounted on a bracket 41 in the vessel 23 and provided with an upward-extending rod 42 in position to be engaged 90 by the bell during the descent of the bell. When the bell strikes the rod 42, it raises the grid or sieve 40 above the water-level in the vessel, thereby breaking and agitating the surface of the water. When the bell descends 95 a little farther and drops carbid into the water, the sudden evolution of gas raises the bell quickly and allows the grid or sieve 40 to drop in its normal position by gravity, again breaking and agitating the surface of the 100 liquid independently of the carbid dropped into the water. In this way the formation of

compact floating masses sufficient to obstruct the feeding of the carbide into the water is prevented.

The gas-educting pipe 45, drain-pipe 46, 5 drain-trap 47, and overflow 48 may be of any desired type without affecting the principle of the invention. So, also, may be the flush-out and the overflow, though I have shown the flush-out and overflow combined, as at 49.

10 For refilling the water-holding vessel 30 and for shutting off the connection 32 when desired funnel 51, valve 52, and valve 53 may be provided.

Having now described my invention, what 15 I claim, and desire to secure by Letters Patent, are the following characteristic features:

1. In combination with a rising and falling gas-holding bell and a holder for carbide or the like carried thereby, of means controlled by 20 the gas produced for compensating for the loss of weight of the carbide, substantially as set forth.

2. In combination with a rising and falling gas-holding bell and a holder for carbide or the like carried thereby, of a water-holding vessel 25 connected to counterweight the carbide-holder and means controlled by the pressure of gas for admitting air to displace the water and lighten the said vessel as the weight of carbide 30 decreases, substantially as set forth.

3. In combination with the water-holding vessel of a gas-generator and with means controlled by the gas for feeding carbide or solid into the water to generate gas, of a mechanical 35 device for agitating the surface of the water independently of the carbide dropped into the water and means for actuating said device by power derived from the gas generated, substantially as set forth.

40 4. The combination with the water-holding vessel of a gas-generator, the rising and falling gas-bell, and means for feeding finely-divided carbide or other granular solid into

the water to generate gas, of means for agitating the surface of the water, comprising 45 a mechanical agitator and means connected to alternately raise it above the normal water-level as the gas-bell descends and depress it beneath the said level of the water as the gas-bell rises, substantially as set forth. 50

5. In combination with the water-holding vessel and an expansible member of a gas-generator and with means controlled by the gas for feeding finely-divided carbide or solid into the water to generate gas, of a mechanical 55 device for breaking up floating accumulations on the surface of the water independently of the carbide dropped into the water and connections therefrom for actuating the same by the movements of the expansible 60 member, substantially as set forth.

6. The combination with the water-holding vessel of a gas-generator, a rising and falling gas-bell, and means for feeding carbide or solid into the water to generate gas, of means for 65 agitating the surface of the water connected to be moved in an opposite direction to the movement of said bell, whereby the formation of floating obstructions may be avoided, substantially as set forth. 70

7. The combination with the water-holding vessel of a gas-generator, a rising and falling gas-bell, and means for feeding carbide or solid into the water to generate gas, of a mechanical 75 device for agitating the surface of the water connected to be actuated in directions opposite to the movement of the gas-bell by power derived from the gas generated, substantially as set forth.

Signed this 21st day of June, 1901, at New 80 York, N. Y.

CHARLES GOODYEAR.
